United States Patent Office

Des. 198,117
Patented Apr. 28, 1964

198,117

SKIM FILTER UNIT OR SIMILAR ARTICLE

William O. Baker, West Covina, and Ernest A. Rodriguez,
La Puente, Calif., assignors, by mesne assignments, to
Shamrock Pool Equipment Company, El Monte, Calif.,
a corporation of California

Filed Nov. 26, 1962, Ser. No. 72,599

Term of patent 14 years

(Cl. D91—1)

FIG. 1.

FIG. 2.

FIG. 3.

FIG. 4.

FIG. 1 is a perspective view showing the front and one side of a skim filter unit or similar article showing our new design;

FIG. 2 is a front elevational view thereof;

FIG. 3 is an elevational view of the side opposite that shown in FIG. 1; and

FIG. 4 is a top plan view thereof.

The fragmentary portions shown in broken lines are included for illustrative purposes only.

We claim:

The ornamental design for a skim filter unit or similar article, substantially as shown and described.
